UNITED STATES PATENT OFFICE

165,754

DUCK DECOY

George L. Herter, Waseca, Minn.

Application January 25, 1951, Serial No. 13,951

Term of patent 14 years

(Cl. D31—4)

To all whom it may concern:

Be it known that I, George L. Herter, a citizen of the United States, residing at Waseca, in the county of Waseca and State of Minnesota, have invented a new, original, and ornamental Design for a Duck Decoy, of which the following is a specification, reference being had to the accompanying drawing, forming part thereof.

Figure 1 is a view in side elevation of a duck decoy, showing my new design.

Figure 2 is a view in top plan of the same.

Figure 3 is a view in front elevation.

Figure 4 is a view in rear elevation.

I claim:

The ornamental design for a duck decoy, substantially as shown.

GEORGE L. HERTER.
